Atty's

UNITED STATES PATENT OFFICE.

GEORGE T. ROHRBACK, OF BUFFALO, NEW YORK.

REFRIGERATOR CAR.

Application filed December 26, 1922. Serial No. 608,902.

To all whom it may concern:

Be it known that I, GEORGE T. ROHRBACK, a citizen of the United States, and a resident of Buffalo, county of Erie, and State of New York, have invented certain new and useful Improvements in Refrigerator Cars, of which the following is a specification, and which are illustrated in the accompanying drawings, forming a part thereof.

10 This invention relates to refrigerator cars of the type having one or more tanks for the reception of ice and salt, and has for its principal objects to provide a valve for controlling the discharge of excess brine from

15 the tank or tanks, that will be automatically locked in either closed or open positions that will open freely and close securely notwithstanding the corrosive action of the brine, that will comprise a minimum of parts and

20 that can be easily and quickly assembled and taken apart.

The Master Car Builders' rules require valves for retaining the brine in the tanks between icing stations located at suitable points along the way, and, while a great variety of constructions for these valves have been proposed and used, they have, to the best of my knowledge, all been defective in one way or another, and have all been unsatisfactory in service. In some, the action of the brine soon rendered the operation uncertain and difficult; in others there was more or less leakage and in all of them there were screw threaded pivots or fastenings which increased the cost of manufacture and were an ever present source of trouble and annoyance in service. In devising the present invention, particular attention has been given to the correction of these defects.

40 In the drawings which show a selected embodiment of the invention,

Fig. 1 is a transverse sectional view showing the tanks in the body of the car;

Fig. 2 is a section taken on the line 2—2 of Fig. 1;

Fig. 3 is a fragmentary detail showing the valve lever in the positions it assumes when the valve is open;

Fig. 4 is an enlarged assembly of the valve with a portion of the valve rod broken away;

Fig. 5 is a plan view of a portion of the valve lever and the fulcrum bracket on which it is pivoted;

Fig. 6 is a sectional view through the valve casing, and a fragment of one of the tanks; and

Fig. 7 is a perspective view of the valve lever.

Referring to Figs. 1 and 2, the reference numeral 10 indicates the body of the car in which the tanks 11, 12, 13 and 14 are suitably mounted as, for example, on floor 15. The roof of the car is provided with hatchways 16, communicating with two of the tanks and closed by suitable covers 17. These hatchways are preferably contracted towards the bottom and plugs 18 are forced tightly against the sides thereof to seal the tank space. All these parts may be of any suitable construction and arrangement.

The tanks are arranged in pairs on opposite sides of the centre line of the car, and a valve 19 controls the discharge of brine from one or more of the tanks. Preferably all the tanks communicate with one valve, but of course, it is immaterial whether one or a plurality of these valves be employed.

As shown in Fig. 6, the valve 19 includes a casing 20, having a cap 21, secured thereto by bolts 22. Adjacent to the bottom there are two inlets 23, by which the valve communicates with the tanks, through nipples 24, threaded into the valve inlets and secured to the tanks by the nuts 25, and the gaskets 26. Between the inlets is an outlet 27, fitted with an elbow 28 connected with a drain pipe 29, which may lead to a drip-pan 30, from which the brine is discharged through a nozzle 31, in the usual way. Between the inlets and the outlet is a valve seat 32, adapted to cooperate with the gasket 33 carried by a valve plug 34. Preferably the gasket is made of rubber and fits about a narrow neck 35 above a head 36. The valve plug is cored out, as indicated at 37, and is equipped with threads 38 to receive a valve stem 39, which extends upwardly through the bearing 40 in the cap 21, and is formed into an eye 41. A valve rod 42 has one end 43 hooked in the eye 41, and the other end 44, hooked about a pintle 45 on a bifurcated valve lever 46 fulcrumed on trunnions 47, mounted in the upper bearings 48 of the fulcrum bracket 49.

By referring to Figs. 1, 2 and 3, it will be seen that the bracket 49 is mounted on a beam 50, of the car, which is slotted at 51 to permit the valve rod to pass therethrough and to swing as the lever is moved from the position shown in Fig. 2 to that shown in Fig. 3. The fulcrum bracket is U-shaped and straddles the slot 51. A hel-

ical spring 52 is coiled about the valve stem 39, and extends between the shoulder 53 on the valve plug and the top 54 of the cap 21, the arrangement being such that 5 the valve is securely pressed against the seat 32 when the lever 46 is lying in the position shown in Fig. 2 with the connection formed by the valve rod and the valve stem substantially free from objectionable 10 slack. To open the valve the lever is rotated clock-wise from the position shown in Fig. 2 to that shown in Fig. 3, during which the pintle 45 passes across the direct line between the eye 41 and the trunnions 47, with the result that the spring 52 locks 15 the lever against the base of the fulcrum 49, thus retaining the valve open until such time as the lever is manually moved past this direct line in a counter-clock-wise direction when the spring will snap the valve 20 shut and seal the gasket against the seat 32. The valve plug 34 has considerable clearance as indicated at 55, which permits it to operate freely even though the walls of 25 the casing and the surface of the plug are rusted or otherwise coated by the action of the brine.

The valve lever 46 is in one integral piece, including the trunnions 47 and the 30 pintle 45, and is preferably made by casting. A fulcrum bracket 49 is also preferably made by casting and the bearings 48 are left open to permit free insertion and 35 withdrawal of the trunnions 47. The hooks 43 and 44 of the valve rod 42 are left open to permit it to be quickly engaged with and 40 disengaged from the eye 41, and the pintle 45. The spring 52 permits insufficient slack 45 in the valve lifting mechanism to allow any 40 of the parts to become disengaged in ordinary use, or during travel, but when it is desired to take the valve apart, the trunnions can be lifted out of the bearings 48, the handlever disengaged from the valve 45 rod and the valve rod unhooked from the eye 41 without the use of any tools and with a minimum of effort. Likewise, in assembling, the reverse order serves to put 50 the parts in operative condition quickly and easily.

I claim as my invention:

1. In a refrigerator car, the combination

of a tank having an outlet, a valve controlling the outlet, and including an upright casing, a valve seat therein, a valve plug 55 for said seat, a valve stem connecting with said plug and projecting upwardly through the casing, an overhead support, a fulcrum bracket on the support and having upwardly opening bearings with a passage between them, a lever bifurcated at one end, having integral trunnions mounted in the bearings and an integral pintle between the furcations, a hook rod for detachably connecting the pintle and the valve stem and 60 resilient means for seating said valve and for preventing accidental disengagement of said hook rod.

2. In a refrigerator car, the combination of a tank having an outlet, a valve controlling said outlet, including an upright casing having a valve seat, a valve plug adapted to close with said seat, a valve stem connected with said valve plug and projecting through said casing, a spring between the 75 upper portion of the casing and the valve plug constantly urging the latter towards said seat, and means for raising the valve plug against the resistance of said spring, including a fulcrum bracket having bearings spaced by an intermediate passage, a bifurcated lever fulcrumed in said bearings and having an intermediately located pintle, a rod in hooked engagement with said pintle and said valve stem, and means for 80 limiting the movement of said lever in both directions but permitting it to swing past center, whereby said valve is held open, against the resiliency of said spring in one position of said lever and is held closed by 85 said spring in the other position of said lever.

3. In a refrigerator car, a combination of a pair of tanks, a valve including an upright casing having inlets communicating with each of said tanks, and an outlet leading therefrom, a valve seat between said inlets and said outlet, a valve plug adapted to close with said seat and having free clearance in said casing, a valve stem connected with said plug and projecting upwardly through said casing, and means for opening and closing said valve.

GEORGE T. ROHRBACK.
